ISAAC A. HEDGES AND JOSEPH M. STORY, OF CINCINNATI, OHIO, ASSIGNEES
TO LANE AND BODLEY, OF THE SAME PLACE.

Letters Patent No. 77,484, dated May 5, 1868.

IMPROVEMENT IN MACHINES FOR SAWING LATH.

The Schedule referred to in these Letters Patent and making part of the same.

TO ALL WHOM IT MAY CONCERN:

Be it known that we, ISAAC A. HEDGES and JOSEPH M. STORY, of Cincinnati, in the county of Hamilton, and State of Ohio, have invented a new and improved Machine for Sawing Laths, and other similar light stuff, and that the following description, taken in connection with the accompanying drawings, hereinafter referred to, forms a full and exact specification of the same, wherein we have set forth the nature and principles of our said improvements, by which our invention may be distinguished from all others of a similar class, together with such parts as we claim, and desire to have secured to us by Letters Patent.

This invention relates to a new and improved machine for sawing laths, and other similar light stuff, and it consists in a novel construction of the machine, arrangement of its parts, &c., as hereinafter fully shown and described, whereby several advantages are obtained, to wit, compactness, rapidity of work, simplicity in the construction of the machine, and the little labor required in attending it while in operation.

In the accompanying sheet of drawings—

Figure 1 is a side view of my invention.

Figure 2, a plan or top view of the same.

Figures 3 and 4, detached perspective views of parts pertaining to the same.

Similar letters of reference indicate like parts.

A is the frame of the machine, on one end of which the saw-arbor B is placed, having a driving-pulley, C, at one end, and a circular saw, D, at the other end, and also a small pulley, E, upon it, from which motion is communicated to a pulley, F, on a shaft, G, located in the lower part of the frame A, underneath the saw-arbor B, said shaft G having two pulleys, a, upon it; around one of which a belt, b, passes, said belt also passing around a pulley, c, on a shaft, H, at the end of the frame A opposite to that where the saw-arbor B is placed.

The shaft H carries a drum, d, around which an endless apron, I, passes, said drum giving motion to the endless apron, which passes around a drum, d', at the opposite end of the box J, through which the upper part of the apron works.

The other pulley, a, on the shaft G, has a belt, e, passing around it, and this belt also passes around two pulleys, f f, on shafts K K, placed on the frame A, parallel with each other and the saw-arbor B, and said belt e also passes around a pulley, g, in a lever, L', having a weight, h, suspended to its free or disengaged end, as shown clearly in fig. 1.

By means of this weighted or loaded pulley g, a requisite degree of tension is given the belt e to drive the pulleys f f, and consequently give motion to feed-rolls i i, on one end of the shafts K K, the feed-rolls being at opposite sides of the saw D, and at the same time gives the necessary weight upon the rolls to cause them to bite, and feed the stuff offered them. The same effect may be produced without the lever, by placing the pulley in a gate sliding between vertical ways, or by other similar means.

One end of the shafts K is journalled in boxes j, which are secured by pivots k in holders l, the latter being provided with cylindrical rods or trunnions m, which are fitted loosely in one side of the frame A, the holders l fitting in recesses n therein, the pivots k being in line at right angles with the shafts K K, and the rods or trunnions m may be secured in place by a set-screw or other means. The opposite ends of the shafts K K, at the inner sides of the feed-rolls, have their boxes o in holders p, the rods or trunnions of which are fitted in the frame A, in the same manner as those of the other boxes.

L is an adjustable table, fitted to the side of the frame A, underneath the feed-rolls i i. This table may be adjusted and secured at any desired point by set-screws r.

On or above the table L is the gauging-bar M, provided with lateral arms or lugs s, which pass through slots in the frame A, and are secured in position by set-screws t. Beyond the adjustable table L there is a fixed table, N, which is narrower than L, and has a parting-strip, u, attached, which terminates in flaring ends, v.

To operate the machine, it is desirable or necessary to adjust the feed-rolls to suit the thickness of the

stuff to be passed through or operated upon. This is accomplished by elevating or depressing one or both of the box-holders *l* *p* of each shaft *K*; and if a material adjustment is necessary, as when very thick stuff is being sawed, the table *L* may be elevated or depressed, and by setting in or out the gauging-bar *M*, the strips sawed from the bolt may be of greater or less thickness, as desired.

The operator feeds the stuff or bolt to the saw, the former being carried to the latter by the first feed-rolls *i*, which will prevent the saw *D*, which is under-cutting, from feeding or moving the stuff or bolt too rapidly. The other feed-roller *i* carries the body of the stuff or bolt, as well as the strip cut from it, to the rear, where they are parted by the strip *u*, the flaring end of which changes the direction of the stuff or bolt as it leaves the rear roll *i*, and the stuff or bolt falls upon the apron *I*, which carries it back to the operator, while at the same time the strip sawed from the stuff or bolt falls from the opposite side of the fixed table *N*.

The operator, therefore, is not required to leave his position while feeding the machine. The weighted pulley *g* serves to drive the feed-rolls *i*, and also serves to keep said rolls down in proper position.

Having thus described our invention, we claim as new, and desire to secure by Letters Patent—

1. The pivoted weighted lever *L'* and pulley *I*, in combination with the belt *e* and pulleys *f* upon the feed-rolls, all arranged and operating as described, whereby the belt is tightened, and the feed-rolls held in their bearings, as herein shown and described.

2. The journal-boxes *j* for the shaft *K*, secured by pivots *k* in the holders *l*, having the vertical shafts *m*, which are adjusted higher or lower in the framing, as herein described, for the purpose specified.

JOS. M. STORY,
ISAAC A. HEDGES.
